UNITED STATES PATENT OFFICE

2,545,626

SPIRAL GEAR PUMP AND ALLIED DEVICE

René Joseph Louis Moineau, Paris, France; Adele Moineau, administratrix of said René Joseph Louis Moineau, deceased, assignor to Robbins & Myers, Inc., Springfield, Ohio, a corporation of Ohio

Application October 2, 1947, Serial No. 777,431
In France December 17, 1946

15 Claims. (Cl. 103—117)

1

The present invention has for its object to provide an improvement in gear type machines (pumps, engines or compressors) in which the gears comprise two spiral elements inside one another, the outer element having one spiral thread or tooth more than the inner element, each thread or tooth of which is constantly in contact in each transverse section with the outer element, the pitches of the threads, which may be constant or not, being for each transverse cross-section in the ratio of the numbers of teeth.

Such machines generally comprise, as known, a stator secured to the case and containing a rotor driven by a flexible drive or a system of joints enabling the rotor to roll in the stator, the axes of the rotor and of the stator, which are parallel to one another being in a direction which is constant in space.

According to the invention, the stator and the rotor are each articulated at a single point located on the corresponding axis of said stator or rotor respectively, the two points of articulation being separate, so that the axes of the stator and of the rotor move in paths describing cones, while said axes remain parallel to each other. A greater simplicity of construction is thus obtained, together with advantageous possibilities of balancing.

I have in the drawings shown several forms of structure applying my invention to the example of a pump, but it will be understood that this is exemplary only of the invention as set forth in the appended claims. In its essence the device to be described may be used to set up a flow in a mobile substance, or by injecting such a substance into the device, the rotor member may be caused to move thus providing an engine or compressor.

Figure 1 is a longitudinal section of a pump according to the invention in which the articulations of the stator and rotor are respectively located at their opposite ends and both within the pump casing.

Figure 2 is a diagram showing the theoretical relationships established.

Figure 3 is a longitudinal section showing a modification of the pump of Figure 1, which is related to the diagram of Figure 2 in vertical alignment, and in which the point of articulation of the rotor is wholly outside the pump casing.

Figure 4 is a longitudinal section of a third form of the invention as applied to a pump in

2

which the point of articulation of the rotor is the center of the pump bearing.

Figure 5 is a diagram showing the determination of the resultant centrifugal force and its moment arm in an element moving as do the rotor and stator according to this invention.

Figure 6 is a diagram showing the manner of achieving a dynamic balancing of a rotor and stator.

10 In Figure 1 the pump is shown with a casing 1 having an intake head 2 bolted thereto and an outlet fitting at 3. In such a relationship the stator and rotor are mounted in the pressure side of the apparatus, although the conditions 15 may be reversed and the rotor driven in either direction. The pump working elements have been disclosed and claimed in Moineau Patents 1,892,217 and 2,028,407 and will hereinafter be referred to as "Moineau elements." The stator 20 5 has an internal thread spirally thereof. This stator may be formed of resilient material such as rubber, or it may be of rigid material, but in any event it must be resiliently mounted adjacent the point of articulation. In Figure 1 I 25 have shown a stator 5 which is made entirely of a resilient material including its flange 6 which is held in place by the intake head, by bolts 8, resulting in the stator having a point of articulation at point A and resulting in the 30 stator being free to move in a path in which its axis describes a cone.

The rotor is shown at 9 having a spiral thread thereon, the pitch of which accords to the principle above announced, to-wit: in this case half that of the pitch of the stator threads. The 35 rotor is coupled by a bonded rubber joint 10 to its operating shaft 11. This results in the rotor having a point of articulation at B and in its having a freedom of movement in a path in which its axis describes a cone reversed end-for-end, as to the free path of the stator axis.

The shaft 11 is held in combination sleeve bearing and packing device forming a part of the pump casing. 13 indicates a rigid coupled joint between the pump shaft 11 and the motor shaft 14, which transmits the pump end thrusts to the bearings of the motor 15. Thus the motor bearings take the pump thrusts and the motor is mounted on the pump casing.

50 In Figure 3 the stator 5 is alike to the stator of the first instance except shown on a larger scale. The intake head 4a is of a modified form. The outlet element at 3a is somewhat modified. The chief difference lies in a modified mode of providing for pump thrust and for the rotor

55

drive. In this case the rotor shaft 17 lies in a cylindrical space 18 within a tube 19, which tube is positioned in the pump casing by suitable bearings 21 and 22. Bearing 22 receives all thrusts while bearing 21 serves strictly in a radial duty. Stuffing box 25 contains suitable packing for the tube 19 with respect to the pump casing so as to make a leak-proof joint.

Bearings 21 and 22 are retained in an arm-like body casting 23. The rotor shaft 17 passes through a flexible packing member 20 which is of resilient, rubber-like material and effects a liquid-tight joint and gives the shaft freedom for angular movement within the tube. The thrust from the rotor shaft is transmitted entirely through the packing member 20 to the tube 19 and thus to the bearing 22. The drive 14a for the rotor shaft is connected thereto by a universal joint connection 16a. In this construction the apex of the cone within which the rotor can move will be at B, as the point of articulation.

In Figure 4 the stator 5b is indicated as made of metal or other rigid material. Bolted to a flange of this stator by bolts 29 is a flexible membrane-like disc 6b, corresponding to flanges 6 of the other forms. This flange is held in place by the intake head 4b secured by bolts 8b to the pump casing. In this case the pump casing again has an arm-like extension 24a within which is a dual direction thrust taking ball bearing 26. The rotor 9b has its shaft 17a in this instance, held in this bearing, and the housing for the bearing is such that the rotor shaft can tilt therein as shown. The drive for the rotor shaft is a bonded rubber coupling 30. The entrance of the rotor shaft into the pump casing is through a flexible sleeve 28, within which is mounted a rigid stuffing box member 27 which contains suitable packing for the rotor shaft 17a. The result of this structure is to provide an articulation point for the stator at A and for the rotor at B. In the second and third modifications, the articulation point for the rotor is in each instance outside of the pump casing, whereas in Figure 1 it is on the inside.

In all of these forms, during the rotation of the rotor inside the stator, the stator can oscillate about the center A of the flange and the rotor oscillates about the center B. These two points in the examples illustrated, are located at the opposite ends of the stator and of the rotor respectively. The relative movement of the stator and of the rotor can take place because in the positions in which the rotor cannot move, the stator is free to move, and in the positions in which the stator cannot move, the rotor can move.

If reference is had to the theoretical diagram of Figure 2 which is on the scale of Figure 3 and in which the centers of oscillation A and B have been shown, if the machine comprises for example a gear element with one tooth (rotor 9) meshing with a gear element with two teeth (stator 5), the theoretical cross-section of the meshing gears at A is represented by the two pitch circles C and D whose centers are A and E. The diameters of said circles are in the ratio of 2 to 1, and the distance AE is equal to the eccentricity.

It will be seen that when the circle D rolls without sliding in the circle C, the axis BE moves in a path describing a cone whose apex is at B and whose altitude is AB. If another section of the stator is considered in the same manner, the pitch circles C' and D' will be obtained whose

centers at A' and E', and it will be seen that the axis AA' of the stator describes a cone whose apex is at A and whose altitude is AB. These two cones have the same half-angle at the apex z. It would be possible to draw other cross-sections on one side or on the other of the flange 6, as for example the cross-section C'' and D'', and the cross-sections would always be found to be in alignment in these conical movements.

The device described therefore definitely enables the rotor to roll correctly in the stator despite the fact that the stator and the rotor are supported respectively at one end only owing to the fact that the two points of articulation are separate.

It will be shown that by suitable choice of characteristics of this machine it can be perfectly balanced dynamically.

The sum F_r of the centrifugal forces applied to the rotor can be considered as being produced by a single mass applied to a point a located at a distance x from the axis AB and equal to: $F_r = mxw$, w being the angular velocity of the axis of the cone. Similarly, for the stator 5 the sums F_s of the centrifugal forces applied at b located at a distance y from the axis AB will, owing to the mass M of the stator be: $F_s = Myw$. The sums F_s and F_r of the centrifugal forces are always in the same plane, that of the two axes EE' and AA', and oppositely directed. For the machine to be balanced, it is necessary and sufficient that the two sums of forces shall be in alignment with one another and that: $mxw = Myw$, or $mx = My$. The velocity w is not involved. The calculation therefore shows and experiment confirms that the machine according to Figure 3 is perfectly balanced with a rubber stator and a rotor, for example, of plastic material or ebonite, the sole condition being that the foregoing equation $mx = My$ is satisfied.

In my Patent No. 1,892,217 I have described families of arrangements of relative spiral threads, and the theory of the pump of which the present invention is a particular type. The flexible mountings with resultant conical paths may be applied wherever in any of the arrangements of the patent there is, as a result of driving one of the pump elements in a rotary manner, a necessity for the other element to move in an orbit. In the present construction one of the two pump elements is fixed against rotation whereas the other is not, which does not apply to all forms shown in my said patent to which reference is hereby made.

The following calculations will be applicable to the structures according to my invention on the basis set forth in the following mathematical discussion, in order to provide for a balance of the parts to assure a high degree of vibrationless operation of the pump so far as its mountings are concerned.

Referring to Figure 5, in which AB represents a homogeneous member of length L and cross-sectional area S, and having a specific gravity of ρ , whose axis passes through a fixed point O, and which is revolving about an axis OO₁ at an angular velocity of w :

If an element of this member, of a length dl is subjected to a centrifugal force, we have

$$df = \frac{P_sdl}{g} w^2 r$$

but $r = x \tan a$, and

$$dl = \frac{dx}{\cos a}$$

substituting we get:

$$(1) \quad df = \frac{Psw^2}{g} \cdot x \tan a \cdot \frac{dx}{\cos a} = \frac{Psw^2}{g} \frac{\sin a}{\cos^2 a} \cdot x dx$$

The resultant centrifugal force is:

$$(2) \quad F = \frac{Psw^2}{g} \frac{\sin a}{\cos^2 a} \int_{x_1}^{x_2} x dx = \frac{Psw^2}{g} \frac{\sin a}{\cos^2 a} \left(\frac{x_2^2 - x_1^2}{2} \right)$$

but

$$E = x_2 \tan a, \text{ or } x_2 = \frac{E}{\tan a}$$

and

$$e = x_1 \tan a, \text{ or } x_1 = \frac{E}{\tan a}$$

$$\therefore F = \frac{Psw^2}{g} \frac{\sin a}{\cos^2 a} \frac{1}{2} \left(\frac{E^2}{\tan^2 a} - \frac{e^2}{\tan^2 a} \right)$$

$$= \frac{Psw^2}{g} \frac{\sin a}{\cos^2 a} \frac{\cos^2 a}{\sin^2 a} \frac{1}{2} (E+e)(E-e)$$

and since

$$\frac{E-e}{\sin a} = L$$

$$F = \frac{Psw^2}{g} L \frac{E+e}{2}$$

Then if W is the weight of the member $= Psl$,

$$(3) \quad F = \frac{W}{g} w^2 \frac{E+e}{2}$$

The moment of the resultant F with respect to the point O is equal to the sum of the moments with respect to this point of the elements of centrifugal force df , and:

$$FX = \int_{x_1}^{x_2} df x$$

Substituting the value for df from (1) and the value for F from (2) in the above equation, we have:

$$X \frac{Psw^2}{g} \frac{\sin a}{\cos^2 a} \left(\frac{x_2^2 - x_1^2}{2} \right) = \frac{Psw^2}{g} \frac{\sin a}{\cos^2 a} \int_{x_1}^{x_2} x^2 dx$$

Simplifying:

$$X \left(\frac{x_2^2 - x_1^2}{2} \right) = \frac{x_2^3 - x_1^3}{3}$$

and

$$(4) \quad X = \frac{2}{3} \left(\frac{x_2^3 - x_1^3}{x_2^2 - x_1^2} \right)$$

Referring now to Figure 6 which shows in diagrammatic representation a rotor and stator, f_1 is the resultant of the centrifugal forces acting on the rotor, and

$$f_1$$

is the resultant of the centrifugal forces acting on the stator. The size and location of these resultants are determined according to Equations 3 and 4 above, and in general these resultants will neither be equal nor opposite. It is therefore necessary to add to the rotor and stator respectively the balancing masses m and m^1 , providing the corresponding forces f_m and f_{m^1} .

In order for the resultants F and F^1 to be equal, it is necessary that the vectors:

$$(5) \quad f_1 + f_m = F = F^1 = f_1 + f_{m^1}$$

and in order that these resultants be opposite, it is necessary that:

$$(6) \quad f_1 l_1 + f_m l_m = f_1 l_1^1 + f_{m^1} l_m^1$$

Since we thus have two Equations 5 and 6, 75

with four unknowns (f_m , l_m , f_{m^1} , l_{m^1}), and since the value l_m and l_{m^1} will usually be dictated by space requirements, we select l_m and l_{m^1} from the range of values available, determine the forces f_m and

5 f_{m^1} by means of Equations 5 and 6, and then calculate the masses m and m^1 which will provide the requisite forces f_m and f_{m^1} . The result, of course, will be a dynamically balanced apparatus.

One other effect to be considered because of 10 the fact that both rotor and stator are turning in a liquid is that of buoyancy of the liquid. For optimum balance, the weight of the moving parts should be equal to the weight of the liquid they displace.

15 It will be clear that numerous modifications may be made without departing from the spirit of my invention, and I therefore do not intend to limit myself otherwise than as pointed out in the claims which follow.

20 Having now fully described my invention, what I claim as new and desire to secure by Letters Patent is:

1. In a machine having two spiral elements one inside the other, the outer element having 25 one spiral thread more than the inner element, each thread of which is constantly in contact in each transverse section with the outer element, the pitches of the threads for each transverse cross section of the elements being in the ratio

30 of the numbers of teeth, a casing in which said elements are mounted, a drive shaft for said inner element rotatable on a fixed axis, a single articulating driving connection between said drive shaft and said inner element, and a single

35 articulating mounting for said outer element at the opposite end from the articulation point of said inner element, so that each of said elements is free to move in a conical path, the apices of said conical paths being oppositely directed relative to each other, and the axes of said outer and inner elements being at all times parallel to each other.

2. The combination of claim 1 in which the 40 sum of the displacements of the inner and outer elements from a line connecting their apices is substantially a constant at all transverse cross-sections of the assembly of the two engaged elements.

3. The combination of claim 2 in which the 45 outer element is fixed against rotation and the inner element is mounted so as to rotate within the outer element.

4. In a machine having two spiral elements one inside the other, the outer element having 55 one spiral thread more than the inner element, each thread of which is constantly in contact in each transverse section with the outer element, the pitches of the threads for each transverse cross section of the elements being in the ratio

60 of the numbers of teeth, a casing in which said elements are mounted, a drive shaft for said inner element rotatable on a fixed axis, a single articulating driving connection between said drive shaft and said inner element, and a single

65 articulating mounting for said outer element at the opposite end from the articulation point of said inner element, said articulating driving connection and said articulating mounting being beyond the interengaged portions of said elements, so that each element is free to move in a conical path, the apices of said conical paths being oppositely directed relative to each other, and the axes of said outer and inner elements being at all times parallel to each other.

5. The combination of claim 4 in which the

sum of the displacements of the inner and outer elements from a line connecting their apices is substantially constant at all transverse cross-sections of the assembly of the two engaged elements.

6. The combination of claim 5 in which the outer element is fixed against rotation and the inner element is mounted so as to rotate within the outer element.

7. In a machine having two spiral elements one inside the other, and each having an effective free end, the outer element having one spiral thread more than the inner element, each thread of which is constantly in contact in each transverse section with the outer element, the pitches of the threads for each transverse cross section of the element being in the ratio of the numbers of teeth, a casing in which said elements are mounted, a drive shaft for said inner element rotatable on a fixed axis, a single articulating driving connection between said drive shaft and said inner element disposed beyond the effective free end of the outer element, and a single articulating mounting for said outer element at the opposite end from the articulation point of said inner element and beyond the effective free end of the inner element.

8. The combination of claim 7 in which the sum of the displacements of the inner and outer elements from a line connecting their apices is substantially constant at all transverse cross-sections of the assembly of the two engaged elements.

9. The combination of claim 8 in which the outer element is fixed against rotation and the inner element is mounted so as to rotate within the outer element.

10. In a pump of the character described having an internally helically threaded stator and an externally helically threaded rotor such that to rotate one with relation to the other enforces a conical path on both, a casing, flexible means for mounting one end only of the stator for ar-

ticulation with reference to said casing, a single flexible articulating means for mounting one end only of the rotor for articulation with reference to said casing, the articulation points for rotor and stator being at opposite ends of the casing.

5 11. The combination of claim 10, in which the articulation point of the rotor is outside the pump casing.

12. The combination of claim 10, in which the 10 stator is formed of flexible material having a flange mounted fixedly in the casing.

13. The combination of claim 10 in which the stator has a rotor engaging surface, at least, formed of flexible material.

15 14. The combination of claim 10 in which the stator is formed of rigid material, and a resilient element is secured to the rigid material and constitutes a flexible mounting therefor.

15 16. The combination of claim 10 in which the 20 rotor shaft is provided with a flexible coupling located within the casing, and a drive shaft for the rotor mounted for rotation on a fixed axis in the head of the casing.
